(57) **CLAIM**

The ornamental design for a massaging device, as shown and described.

DESCRIPTION

FIG. 1 is a front isometric view of a massaging device showing my new design;

FIG. 2 is a rear isometric view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings are for the purpose of illustrating portions of the massaging device, which form no part of the claimed design.
